ELECTRICAL DISPLAY DEVICE

Clyde H. Clement, Phoenix, Ariz.

Application May 17, 1955, Serial No. 36,033

Term of patent 14 years

(Cl. D80—1)

Figure 1 is a side elevational view of an electrical display device showing my new design therefor;

Figure 2 is a plan view thereof; and

Figure 3 is an end view thereof.

I claim:

The ornamental design for an electrical display device, as shown.
